UNITED STATES PATENT OFFICE.

CHARLES I. LONGENECKER, OF MILWAUKEE, WISCONSIN, ASSIGNOR TO C. H. & E. MANUFACTURING COMPANY, OF MILWAUKEE, WISCONSIN.

COMBUSTION-ENGINE.

1,285,265.

Specification of Letters Patent. Patented Nov. 19, 1918.

Application filed April 8, 1918. Serial No. 227,356.

To all whom it may concern:

Be it known that I, CHARLES I. LONGENECKER, a citizen of the United States, and resident of Milwaukee, in the county of Mil-

waukee and State of Wisconsin, have invented certain new and useful Improvements in Combustion-Engines; and I do hereby declare that the following is a full, clear, and exact description thereof.

10 My invention relates to new and useful improvements in heavy fuel combustion engines, particularly those of the stationary or marine type.

In practically all internal combustion engines which operate on a heavy or low grade of fuel, water or its vapor is added to the fuel in the mixing chamber before the combustible mixture is passed to the engine cylinder, this being done to dampen the mixture and prevent pre-ignition. It is one object of this invention to provide an improved means for supplying water in varying amounts, the quantity depending on the speed of the engine and ranging from zero 20 for all light running to a considerable degree at maximum operation. In this connection a water reservoir of improved design is employed which is so connected to the cooling jacket of the engine cylinder 25 that the water circulates through both.

An additional object is to provide an improved constant level fuel reservoir in which two grades of fuel may be stored, one grade being adapted for initial operation of the 30 engine while the second grade is used for general operation after the same has been started. The inlet between the fuel reservoir and the mixing chamber is such that the latter may be selectively connected with 35 either of the compartments of the reservoir containing the different grades of fuel, and also said inlet is so positioned with respect to the constant fuel level that leakage is obviated.

40 A further object is to provide an air intake of improved construction whereby a supply of filtered air may be readily drawn into the mixing chamber by the suction of the moving piston in the engine cylinder, a 45 filtering breather of somewhat similar construction being employed on the crank case to relieve compression and vacuum therein.

A still further object is to effectively combine all of the foregoing features so that an

engine of simple and effective formation will 55 result and one in which a minimum quantity of fuel may be used to procure maximum power.

With these and other objects in view the invention consists in certain novel features 60 of construction, combination and arrangement of parts which will be hereinafter more particularly described and claimed and shown in the drawings, in which:

Figure 1 represents a side elevational 65 view, partly in section, of an internal combustion engine constructed in accordance with my invention.

Fig. 2 is a front elevational view also partly in section of the mechanism depicted 70 in Fig. 1.

Fig. 3 is an enlarged vertical sectional view through the upper portion of the engine cylinder and associated parts.

Fig. 4 is a horizontal section taken on the 75 plane of the line 4—4 of Fig. 3.

Fig. 5 is a similar view on the plane of the line 5—5 of the same figure showing more particularly the construction of the upper end of the engine cylinder. 80

Fig. 6 is a detail vertical sectional view taken on the line 6—6 of Fig. 7.

Fig. 7 is a plan view of the two compartment fuel reservoir removed from the parts to which it is usually connected. 85

Fig. 8 is a vertical sectional view of the constant level water reservoir and a fragment of the water jacket of the engine cylinder.

Fig. 9 is an elevational view, partly in 90 section, of the water reservoir.

Fig. 10 is a detail sectional view of the fuel pump and the adjacent portion of the base of the engine, oil being forced from the latter to the fuel reservoir thereby, and 95

Fig. 11 is an enlarged detail sectional view through the crank case breather.

In the accompanying drawings for convenience in illustration a single cylinder engine equipped with my improvements is 100 shown, it being understood, however, that the latter are capable of use on multi-cylinder engines as well.

The engine includes a cylinder 1, the major portion of which is surrounded by a water 105 jacket 2, a crank case 3, and a crank shaft 4 having fly-wheels 5 disposed on its opposite ends, all of which parts are supported on a

suitable hollow base 6 in which fluid fuel oil is stored. The head of the cylinder is provided with inlet and exhaust valves 7 which are successively opened by the movements of tappets 8 against the upwardly projecting valve stems 9; said tappets being in turn operated by tappet rods 10 that are vertically reciprocated by means of cams on a cam shaft 11 as is customary in machines of 10 this character.

The fuel for reciprocating the piston within its cylinder 1 is led thereinto through a passage-way 12 in the head of the same as most particularly disclosed in Fig. 3. The 15 passage-way 12 is in communication with the lower end of a vertical mixing chamber 13, the same being preferably bolted as at 14 to the head of the cylinder 1 and is cylindrically elongated, it being substantially the same 20 diameter throughout its length except at its extreme upper end where it is contracted as at 15 to provide a venturi.

Surrounding this upper end of the mixing chamber 13 and preferably formed integrally therewith is a two compartment fuel reservoir 16, the same being divided by partition walls 17 and 18. The partition wall 18 is relatively thick and is formed with a horizontal cylindrical bore 19 which extends 30 through the outer wall of the reservoir as well as the inner wall and into the mixing chamber at the venturi 15. In this connection it will be noted that said inner wall of the reservoir is the wall of the mixing chamber 13. The partition 18 in addition has a 35 pair of spaced vertically positioned ducts 20 and 21 which have their upper ends in communication with the bore 19, while their lower ends communicate respectively with the several compartments of the reservoir. 40

Disposed for rotative movement in the bore 19 is a cylindrical hollow nozzle 22, the inner end of which extends into the mixing chamber as best shown in Fig. 3. The wall 45 of the nozzle intermediate its ends is provided with a pair of openings 23 and 24, the same preferably being positioned approximately 180° apart. A handle 25 projects laterally from the outer end of the nozzle 22 for convenience in rotating the same to selectively dispose the openings 23 and 24 in alignment with the ducts 20 and 21 respectively to thus permit communication between either compartment of the reservoir 50 and the mixing chamber 13.

A bracket 26 secured to the outer wall of the reservoir 16 is adapted to receive the stem 27 of a control valve by which the opening of the nozzle 22 is regulated, said 55 stem being threadedly positioned in said nozzle. The bracket is also adapted to provide a stop for one end of an expansile spring 28 which bears against the outer end of the nozzle 22 for the purpose of retaining the same in the bore 19.

One of the compartments of the fuel reservoir 16 is preferably larger than the other for the reception of a quantity of gasoline or other highly volatile fuel for initial operation of the engine, access to this compartment being gained through an opening normally closed by a screw plug 29. The other compartment is always kept filled to a constant level with a heavier or lower grade of fuel oil which is used for operating the 75 engine after the same has once been started. This heavier fuel oil is pumped from the base 6 of the engine in which it is stored to the fuel reservoir. (The heavy broken lines in Figs. 1 and 2 indicate the direction of flow of 80 this heavy fuel oil.)

The pump for causing this circulation is indicated at 30 as best shown in Fig. 10. The plunger rod 31 of the pump is preferably reciprocated by the action of an eccentric 32 on 85 the cam shaft 11.

At times the pump may supply a larger quantity of fuel oil to the reservoir than can be consumed, therefore the proper compartment of the latter is provided with an 90 outlet 33 in its bottom whereby the surplus may flow back into the base 6 of the engine as indicated by the heavy dot and dash lines in Fig. 1. However, in order to retain the fuel in this compartment at a constant level 95 the outlet 33 is surrounded by an overflow wall 34. To obviate any possibility of leakage of the fuel oil into the mixing chamber, the plane of the top of the overflow wall 34 is below the plane of the bottom of the 100 bore 19 as indicated in Fig. 6; thus it is necessary that the fuel oil be sucked from the nozzle 22 by the action of the piston.

Referring again to the upper end of the mixing chamber 13 it will be seen that an 105 air inlet 35 is secured thereto, said inlet having a centrally apertured partition wall 36 intermediate its ends, the same being adapted to form a valve seat for the valve disk of a compensating valve 37. The same is 110 designed to close outwardly against the inner surface of the valve seat whereby to permit the same to be readily opened and closed varying amounts corresponding with the suction of the engine piston. The wall 115 36 also is provided with an opening 38 which is not closed by the valve 37, the same thus permitting a predetermined quantity of air to leak into the mixing chamber under all circumstances.

It is essential that pure air free of all extraneous matters be taken into the mixing chamber, therefore I provide a filtering device which consists of a preferably cylindrical casing 39 open at one end and closed 125 at the other. The open end of the casing 39 is covered with a reticulated plate 40 and spaced inwardly therefrom is a second reticulated plate 41 between which a suitable filtering medium 42 is packed. The space 130

between the closed end of the casing 39 and the inner plate 41 is in communication with the air inlet 35 to the outer side of the compensating valve 37.

- 5 After the engine has started and is operating on the heavy or low grade fuel oil, water or its vapor is fed into the mixing chamber as hereinbefore mentioned. For this purpose a water supply nozzle 43 is
 10 extended into the air inlet through one wall thereof and positioned outwardly of the compensating valve 37. Inasmuch as the partition wall 36 is disposed horizontally, the water supply nozzle 43 is positioned directly above the opening 38 in said wall whereby liquid may drop past the latter without striking the same. The nozzle may be of any preferred construction and is controlled by a conventional valve 44.
 15 For the same reason that the fuel nozzle 22 is spaced above the constant level of the oil or fuel supply, the nozzle 43 is above the level of the water in the reservoir 45, communication between the latter and said
 20 nozzle 43 being procured through an inclined pipe 46. The water reservoir 45 is in the form of a substantially rectangular casing having an enlarged filling opening 47 in its top and an outlet 48 in one side wall adjacent its inclined bottom 49. The outlet 48 is adapted to communicate with an opening 50 in the wall of the water jacket 2. From the top of the water jacket extends a discharge pipe 51 the upper end
 25 of which projects laterally and over the opening 47 in the reservoir 45.

When the water flows from the discharge pipe 51 into the reservoir 45 a portion of the same drops into a pocket 52 in the upper portion thereof, which pocket is constructed of a horizontal wall 53 and a vertical wall 54. The first mentioned wall extends approximately half the width of the reservoir 45 and has its outer edges formed integrally with the side walls of the reservoir, its inner edge being connected with the vertical wall 54. The intermediate portion of the vertical wall has a notch 55, the distance between the bottom of the same and the horizontal wall 53 determining the height of the water in the pocket. A constant level of water is thereby obtained, such level being always below the plane of the water supply nozzle 43. From Fig. 8 it will be seen that the inclined pipe 46 which connects such nozzle with the reservoir 45 opens into the pocket 52. Also in this figure is illustrated a vent 56 in the horizontal wall 53 whereby upon the cessation of the operation of the engine and the consequent stoppage in the circulation of the water, the supply of water in the nozzle 43 and in the pipe 46 as well as that in the pocket may drain therefrom and thus prevent freezing.

The amount of combustible mixture containing the fuel oil and the water vapor passing from the mixing chamber 13 to the engine cylinder is also automatically regulated by a butterfly valve 57 disposed in the lower end of said chamber. The stem of this valve projects outwardly of the mixing chamber and has a crank 58 fixed thereto to which is pivoted an operating rod 59. This rod extends downwardly to a point adjacent the base of the engine where it is connected by any preferred mechanical movement with a governor 60 on one of the fly-wheels 5.

The lower portion of the crank case 3 adjacent its connection with the base 6 is provided with a breather 61, the same consisting of a cylindrical casing 62 open at its top and closed at its bottom and provided with a circular hole in its side wall, said hole being surrounded by a coupling flange 63. The inner surface of the wall of the casing between said hole and its open end has an inwardly extending flange 64 on which is seated a reticulated screen 65, the same being adapted to coöperate with a similar screen 66 which closes the open end of the casing. Between the two screens is placed a suitable filtering material whereby air drawn into the casing will be freed of any direct or other foreign matter. The open end of the casing is protected by a cover plate 67, the same having its annular portion laterally directed to parallel the wall of said casing; the cover plate is spaced from the casing as will be most clearly seen in Fig. 11.

The following is the substantial operation of my invention:—The gasoline compartment of the fuel reservoir 16 is filled with fuel for initial operation of the engine and the hollow base 6 is provided with a necessary supply of heavier or lower grade fuel oil for operation of the engine after the same has once been started; the water reservoir 45 is filled through the opening 47 with water until the level of the same is approximately at the bottom of the pocket 52 or higher, some water being necessarily trapped in the latter. The engine is now ready to be started by any suitable cranking means, the butterfly valve at this time being completely open, while the compensating valve is fully closed.

Inasmuch as there is a considerable suction within the mixing chamber and the adjacent portion of the air inlet member 35 when the engine piston is moved downwardly on its intake stroke, a quantity of gasoline will be drawn into the mixing chamber from the nozzle 22, the latter having its opening 23 alined with the duct 20 leading from the gasoline compartment of the fuel reservoir. This gasoline being vaporized and drawn into the cylinder of the engine is exploded, and after several such explosions have occurred and the engine is

operating successfully, the nozzle 22 is rotated by means of its handle 25 to align the opening 24 with the duct 21 and thus permit heavy fluid fuel to be drawn into the 5 mixing chamber, the use of gasoline being thereby discontinued until it is again necessary to start the engine at a subsequent time.

As the engine reaches its maximum free-running speed, the butterfly valve 57 will 10 almost completely close to limit the supply of fuel drawn into the mixing chamber. Thus until the engine is running under load a very small quantity of fuel can be drawn 15 into the mixing chamber or into the engine cylinder. This butterfly valve being thus positioned the suction of the piston will be insufficient to actuate the compensating valve or to draw water into the mixing 20 chamber from the supply nozzle 43. In other words the compensating valve is at 25 this time closed so that a negligible quantity of air is mixed with the fuel; it is also necessary that the compensating valve remain closed as the fuel must be sucked from its normal level and through the nozzle 22 as hereinbefore described.

As load is applied to the engine its speed will decrease slightly and the butterfly valve 57 will open. At approximately five per 30 cent. (5%) load the compensating valve will commence to open and permit increasing 35 quantities of air to enter the mixing chamber; and when the engine reaches a fifty per cent. (50%) load the compensating valve is opened to such an extent and the suction is sufficiently great to draw water into the mixing chamber from the water supply nozzle 43. From this point until maximum load is reached increasing quantities of water are 40 supplied to the mixing chamber. It is, however, only after the suction within the mixing chamber reaches a considerable degree 45 that water is drawn thereinto, this being due to the fact that the water supply nozzle 43 is normally out of the higher air velocities, it being positioned externally of the compensating valve.

After the engine has started to function normally the fuel oil will be regularly and 50 systematically pumped from the supply in the hollow base 6 to the fuel reservoir 16 by means of the pump 30. This fuel oil is retained at a constant level in the reservoir in the manner hereinbefore set forth.

55 The water which is sucked from the nozzle 43 as has been previously explained is procured from the pocket 52 of the water reservoir. The large supply of water in the reservoir 50 below the pocket 52 is caused to circulate through the water jacket of the engine after the latter has become considerably heated, and after steam has been generated to an extent sufficient to force the water upwardly through the discharge pipe 51. The 60 water from such discharge pipe thus retains

the supply in the pocket 52 at a constant level. As the water in the reservoir 45 gradually evaporates an additional supply is poured thereinto through the filling opening 47.

70 When the engine ceases operations the water in the pocket 52 will be drained therefrom and into the lower portion of the reservoir 45 through the vent 56. Also inasmuch as the supply nozzle 43 and the pipe 46 are 75 above the bottom of the pocket 52 the same will also be drained when the pocket is emptied.

Various minor changes may be made in 80 the form and proportion of the various parts of the invention without departing from or sacrificing any of the features thereof as outlined in the appended claims.

I claim:

1. The combination with an internal combustion engine including a carburetor, a cylinder and a water jacket surrounding the cylinder and provided with an inlet and an outlet opening, of a main water reservoir having its lower portion in communication 90 with the water jacket inlet, a pocket in the upper portion of the reservoir adapted to overflow thereinto, means for supplying said pocket with water discharged through the outlet of the water jacket, and means for 95 supplying water from said pocket to the carburetor.

2. The combination with an internal combustion engine including a carburetor, a cylinder and a water jacket surrounding the cylinder provided with an inlet and an outlet opening, of a main water reservoir having communication at its lower portion with the inlet opening of the water jacket, a pocket in the reservoir arranged to overflow 100 thereinto, a pipe extending from the outlet opening of the water jacket and adapted to discharge in the pocket, and means for 105 conveying water from the pocket to the carburetor.

110 3. The combination with an internal combustion engine, of means for supplying fluid thereto including a constant level reservoir comprising a casing having a large inlet opening in its top, a horizontal wall in said casing intermediate its top and bottom, the ends of said wall being secured to the sides of the casing, a vertical wall extending upwardly from the free edge of the horizontal wall whereby to form a pocket, said pocket 115 being in position to receive fluid from the inlet opening, excess fluid received therein being adapted to overflow the vertical wall, and an outlet from the casing in communication with said pocket.

120 4. The combination with an internal combustion engine including a cylinder and a water jacket surrounding the same, the latter having an inlet and an outlet opening, of means for supplying fluid to the engine 130

including a constant level reservoir comprising a casing having an inlet, a pocket in the casing above the bottom thereof and in position to receive fluid from the inlet, excess fluid received in the pocket being adapted to overflow the wall thereof into the main portion of the casing, said casing having an outlet communicating with the inlet of said water jacket, an outlet from the casing in

communication with said pocket, and a pipe 10 extending from the outlet of the water jacket to the inlet of said casing.

In testimony that I claim the foregoing I have hereunto set my hand at Milwaukee, in the county of Milwaukee and State of 15 Wisconsin.

CHARLES I. LONGENECKER.
